UNITED STATES PATENT OFFICE

2,525,184

SPINDLE MOISTENER MECHANISM

John D. Rust, Memphis, Tenn.

Application March 27, 1947, Serial No. 737,702

12 Claims. (Cl. 56—41)

1

My invention which relates to the art of cotton picking machines in general and those of the Rust type in particular has for its objects:

1. To provide a spindle moistener which will cure certain deficiencies present in those moisteners heretofore used.

2. To provide a floating moistener composed of superposed wheels having inherent provisions for preventing misalignment of the wheels.

3. To provide a moistener which will not become clogged by cotton.

4. To provide an improved means for applying water to the periphery of the wheel rings.

5. To eliminate any rotating shaft or roller journalled at the bottom of the series of wheels where the cotton waste is discharged.

6. To provide an improved liquid dispensing device for delivering liquid to the wheel-moistening sponge.

Other objects will in part be obvious and in part be pointed out hereinafter.

To the attainment of the aforesaid objects and ends, invention resides further in the novel details of construction, combinations and arrangements of parts all of which will first be described in detail and then be specifically pointed out in the appended claims, reference being had to the accompanying drawings in which:

Fig. 1 is a plan view of the moistener wheel assembly, the stabilizing roller and the liquid applicator shown in their relation to the picking spindles.

Fig. 2 is an elevation of the same looking in the direction of the arrow *x*.

Fig. 3 is a detail vertical section on the line 3—3 of Fig. 1.

Fig. 4 is a magnified view in section of a portion of one wheel.

Fig. 5 is a similar view taken 180° from that of Fig. 4.

Fig. 6 is a schematic view of the complete device, parts being broken away and other parts being shown in section.

Fig. 7 is a detail elevation showing how the two sections of a wheel may be spread apart slightly to take up wear on the spindle engaging edges of the wheels.

In the drawings in which like numerals indicate like parts in all the figures, 1 represents the chain of spindles which in practice are carried in a direction from left to right in Fig. 1 and dragged through the moistener between the wheels thereof.

The spindle moistener proper comprises a plurality of wheels composed of wheel elements each having an inner rim 2 and a rim flange 3 and a

2

single spoke 4. Over the rim 2 of each wheel element is molded a wiping face 5 of rubber or other suitable material (see Figs. 3, 4 and 5). The spokes 4 of the wheel elements 2 lie at one side of the same and in planes normal to the axes of the wheel elements 2.

Except for the top and bottom parts, each wiper wheel is composed of two identical wheel elements 2, 3, 4, 5 with the spokes in face to face contact and spot welded or otherwise secured together as a unit as at 6, Figs. 1 and 3. The rims of the wheel sections are inclined at about 45° to the planes of the spokes 4 and flange 3 so that when a pair of wheel elements are assembled together the inclined rims will present a V-shaped peripheral groove in which the rubber of the wiping face 5 in part lies as best shown in Figs. 3, 4, and 5. The spokes 4 are drilled to fit the bolt 7 on which the wheels are securely held by spacers 8, nuts 9 and a washer 10. When nut 9 is drawn tight there will be spaces 33 for the spindles 1 to be drawn through in frictional engagement with the wheel.

An angle iron post 11 carries brackets 12 having holes 13 which receive shaft 14 which is journalled in stabilizing roller 15. 14a is a strap iron wing welded to shaft 14 which prevents same from dropping through the holes 13 and from rotating. The brackets 12 are located short of the top and bottom levels of the wheel so that the correspondingly shortened roller 15 will not become entangled with cotton on the floor of the machine, or be in a position where cotton would wind up around the bottom of the roller which eventually would ball up and force the rings out of alignment. The angle iron post 11 is suitably secured to the frame 16 of the machine.

17 is a U-shaped elongated body which is welded or otherwise secured to a rod or pin 18 which projects through openings (top and bottom) in the frame 16. To the body 17 is hinged a flat plate 19 between which and a flap 22 of ducking, a column of sponge 21 is held by clip 17a. The spring 20 is secured to frame 16, the free end of the spring lying against plate 19 under slight tension to press the ducking against the peripheries 5 of the moistening wheels (see Figs. 1 and 2).

By referring now more particularly to Fig. 6 it will be seen that liquid is conducted from a reservoir 31 (carried by the cotton picking machine not shown) through a pipe 32 to a regulating valve. The regulating valve comprises a cup 27 having a threaded cap 34 for the stem 30 which carries a plunger 29. A natural sponge 28 is

located in the inlet end of the cup and may be more or less compressed by the screw plunger 29, 30 as will be more clearly explained presently. The cap 34 has an outlet 35 through which liquid gravitates over a lip 36 and drops onto a sponge strainer 25, 26 in a (preferably) transparent container 24 which is positioned to act as a windshield for the small stream of liquid flowing from outlet 35. Liquid passes from container 24 through a pipe line 23 from which it drips onto the sponge 21.

The regulator valve 27, etc. is preferably located on the machine at a place convenient for observation and adjustment by the operator. The flow of liquid is regulated by the screw 30 acting on the piston or disc 29 which compresses the sponge 28 to the degree necessary to permit only the desired flow of liquid to pass through. The advantage of this arrangement is that the desired rate of flow can be maintained indefinitely once the valve has been adjusted, because the accumulation of small particles of foreign matter on the sponge does not perceptibly affect the flow. By making the cup 24 of glass or other suitable transparent material the operator may at all times be able to observe the flow of liquid.

Attention is called to the fact that the moistener of my present invention differs from that of my application Serial No. 691,781 filed August 20, 1946, now Patent No. 2,483,557 in that it has one spoke per wheel unit, which provides for a center mounting. With the arrangement of centerless rings, as shown in the above application, it was found that on occasion one or more of the rings would get out of alignment and cause damage to the machinery. The principal cause for the dislocation of those rings was found to be the winding up of cotton around the bottom of the guide rollers which, as before intimated, would eventually ball up and force the rings out of line. In order to overcome this difficulty and still avoid the difficulties encountered with the older type of two-spoke wheels which were journaled in bearings, I have utilized the desirable features of both and eliminated their objectional features in devising the present arrangement.

It is to be observed (see Figs. 2 and 3) the entire wheel assembly has no center bearing but floats freely in its working position as shown in Fig. 1. The wheels are collectively rotated by the spindles passing between them as indicated by the arrow *a* in Fig. 1 and the forward motion of the assembly of wheels is prevented by the vertical roller 15. The entire wheel assembly is supported against vertical movement by the spindles 1 only and is held against horizontal movement by its contact with the roller 15, the moistener (17 to 22 inclusive), and the spindles, making what may be called roughly a three-point contact.

As before pointed out, the wheels are made, preferably, in halves, both metal and rubber, which halves can be clamped back to back to form one complete wheel. The sheet metal spokes 4 may simply be clamped together face to face by the long bolt 7 or they may be spot welded, as at 6, if desired.

The reason for the divided wheels is to provide a simple and easy means of compensating for the wear on the rubber by the action of the spindles. When the rubber becomes worn too much to make proper contact with the spindles, the wheel halves may be pried apart with a screw driver or the like (see arrow Fig. 7) to compensate for the wear.

From the foregoing description taken in connection with the accompanying drawings it is thought the construction, operation and advantages of my invention will be clear to those skilled in the art.

What I claim is:

1. In a spindle moistening apparatus wherein spindles are drawn through spaces between rotary moistening rings, the improvement which comprises a rotary moisture applying device that includes a series of superposed sheet metal wheels each wheel comprising two wheel elements each having a rim and a spoke, the spoke lying in the plane of an edge of the rim, said wheel elements being situated with their spokes in face to face contact thereby disposing the same wheel elements in pairs, and means securing all said spokes rigidly together along the axis of the wheels with spindle passages between adjacent pairs of wheels, the whole constituting a single unit.
2. In a spindle moistening apparatus wherein spindles are drawn through spaces between rotary moistening rings, the improvement which comprises a rotary moisture applying device that includes a series of superposed sheet metal wheels each wheel comprising two wheel elements each having a rim and a spoke, the spoke lying in the plane of an edge of the rim, said wheel elements being situated with their spokes in face to face contact thereby disposing the same wheel elements in pairs, means securing all said spokes rigidly together along the axis of the wheels with spindle passages between adjacent pairs of wheels, the whole constituting a single unit, and a rubber covering over the rim of each wheel.
3. In a spindle moistening apparatus wherein spindles are drawn through spaces between rotary moistening rings, the improvement which comprises a rotary moisture applying device that includes a series of superposed sheet metal wheels each wheel comprising two wheel elements each having a rim and a spoke, the spoke lying in the plane of an edge of the rim, said wheel elements being situated with their spokes in face to face contact thereby disposing the same wheel elements in pairs, means securing all said spokes rigidly together along the axis of the wheels with spindle passages between adjacent pairs of wheels, the whole constituting a single unit, and an integrally formed rubber covering over the rim of each wheel.
4. In a spindle moistening apparatus wherein spindles are drawn through spaces between rotary moistening rings, the improvement which comprises a rotary moisture applying device that includes a series of superposed sheet metal wheels each wheel comprising two wheel elements each having a rim and a spoke, the spoke lying in the plane of an edge of the rim, said wheel elements being situated with their spokes in face to face contact thereby disposing the same wheel elements in pairs, means securing all said spokes rigidly together along the axis of the wheels with spindle passages between adjacent pairs of wheels, the whole constituting a single unit, said securing means comprising a bolt and nut passing through said spokes, and spacers on said bolt between adjacent wheels.
5. In a spindle moistening apparatus wherein spindles are drawn through spaces between rotary moistening rings, the improvement which includes an unmounted spindle moistening rotary element, means for supporting said rotary element from following the spindles to which it is applied, and a combined moisture applying and

rotary element supporting device contacting the periphery of said rotary element at the aft side of the same.

6. In a spindle moistening apparatus wherein spindles are drawn through spaces between rotary moistening rings, the improvement which includes a free floating spindle moistening rotary element, means for restraining said rotary element from following the spindles to which it is applied, and a moisture applying device contacting the periphery of said rotary element at the aft side of the same, said moisture applying device being pivotally mounted at top and bottom and including vertical hinged elements between which fibrous material is clamped, and means yieldingly pressing said fibrous material of said pivoted device against the moistening rings.

7. In a spindle moistening apparatus wherein spindles are drawn through spaces between rotary moistening rings, the improvement which comprises a spindle supported rotary moisture applying device that includes a series of superposed wheels, each having a rim and a spoke, means securing said spokes rigidly together along the axes of the wheels with spindle passages between adjacent wheels and flexible covering over the rim of each wheel, the whole constituting an unmounted unit, and means for restraining said moisture applying device from following along with said spindles.

8. In a spindle moistening apparatus wherein spindles are drawn through spaces between rotary moistening rings, the improvement which comprises a spindle supported rotary moisture applying device that includes a series of superposed wheels, each having a rim and a spoke, means securing said spokes rigidly together along the axes of the wheels with spindle passages between adjacent wheels and flexible covering over the rim of each wheel, the whole constituting an unmounted unit, and means for restraining said moisture applying device from following along with said spindles and means for supporting said rotary moistening device from following the spindles to which it is applied, said means including a stabilizing roller for contacting the periphery of said rotary moistening device at the fore side of the same, said moisture applying device being substantially longer axially than said roller.

9. In combination, a free floating rotary spindle moistener including a series of superposed rings spaced apart for the passage of spindles between adjacent rings and in contact with the same, a stabilizing roller held against the peripheries of said rings at the foreside of the same, and a roller moistening and rotary moistener positioning device contacting said rings at the aftside of the same, said stabilizing roller, said combined

device, and said spindles constituting the sole means for holding said rotary moistener in place.

10. In a spindle moistening apparatus wherein spindles are drawn through spaces between rotary moistening rings, the improvement which comprises a moistener composed of a set of wheels having a common axis, each wheel comprising two identical wheel elements, each wheel element having a rim and an internal flange located at one edge of said rim and lying in a plane normal to said axis, said two wheel elements being secured together with their flanges in face to face contact, and means spacing the several wheels apart in axial alignment and securing the set of wheels together as a unit, to provide spindle passages between the several wheels.

11. In a spindle moistening apparatus wherein spindles are drawn through spaces between rotary moistening rings, the improvement which comprises a moistener composed of end wheels and a set of intermediate wheels having a common axis, each intermediate wheel comprising two identical wheel elements, each wheel element having a rim and an internal flange located at one edge of said rim and lying in a plane normal to said axis, said two wheel elements being secured together with their flanges in face to face contact, and means spacing the several wheels apart in axial alignment and securing the set of wheels together as a unit, to provide spindle passages between the several wheels.

12. In a spindle moistening apparatus, a rotary moistener composed of a set of superposed wheels secured together as a unit and spaced apart to permit the spindles to be drawn through between said wheels, and means comprising the sole support for said unit, said means comprising a roller engaging the peripheries of said wheels at the fore side of the moistener and an element contacting the peripheries of said wheels at the back side of the moistener and said spindles, making a three-point contact with the moistener.

JOHN D. RUST.
